UNITED STATES PATENT OFFICE.

JACOB H. SHANK, OF CREWE, VIRGINIA, ASSIGNOR OF ONE-THIRD TO JAMES L. JONES, OF CREWE, VIRGINIA.

RAILWAY-RAIL.

1,152,233.

Specification of Letters Patent.

Patented Aug. 31, 1915.

Application filed April 17, 1915. Serial No. 22,072.

To all whom it may concern:

Be it known that I, JACOB H. SHANK, a citizen of the United States, residing at Crewe, in the county of Nottoway and State of Virginia, have invented new and useful Improvements in Railway-Rails, of which the following is a specification.

This invention relates to improvements in the construction of railway rails.

10 In carrying out my invention I propose to construct a compound rail of a simple but strong design wherein the joints thereof shall be staggered so that none of the meeting ends of any of the elements comprising 15 the rail may be disposed opposite each other and also whereby a substantially continuous rail will be provided.

It is also my purpose to construct a compound rail which shall comprise an intermediate member and side members, the same being so arranged when assembled that an impact of force upon the head of the rail will have a tendency to bring all of the members into tight engagement with each other 25 to afford a smooth surface for the wheels of the rolling stock and to assure the proper alignment of the members at the head of the rail.

It is a further object of my invention to 30 so arrange the members comprising my rail that the rail will be afforded a certain and desired amount of yieldability when under the stress of the rolling stock passing thereover, and thus obviate the liability of breakage incident to a positively rigid rail.

It is a still further object of the invention to construct a compound rail wherein the employment of the usual nuts and bolts or analogous devices commonly employed in 40 connecting the elements of a compound rail will be entirely dispensed with.

A still further object of the invention is to provide tie plates that are spiked to the ties upon which the rails rest and to provide the said plates with hooks or fingers which engage with the lower longitudinal edges of my rail to sustain the said rail upon the ties.

Another object of the invention is to arrange upon the underface of the rail, between the ties, adjustable means for swinging or tilting the base portions of the outer members of the rail to force the upper portions thereof into contact with the opposite sides of the upper portion of the interme-

diate section of the rail, as well as to brace and reinforce the rails between the said ties.

With the above and other objects in view the improvement resides in the construction, combination and arrangement of parts set forth in the following specification and falling within the scope of the appended claims.

In the drawings, in which there is exemplified a simple and satisfactory reduction of the improvement to practise, as it now appears to me: Figure 1 is a top plan view of a rail constructed in accordance with my invention and showing the same secured upon the ties, Fig. 2 is a side elevation of the same, Fig. 3 is a transverse sectional view, 70 upon an enlarged scale, taken approximately on the line $x-x$ of Fig. 1, Fig. 4 is a similar sectional view approximately on the line $y-y$ of Fig. 1, Fig. 5 is a perspective view of one of the tie plates, Fig. 6 is a similar 75 view of one of the side members of the rail, Fig. 7 is a plan view illustrating the manner in which the joints are broken when the members comprising the rail are being assembled, Fig. 8 is a perspective view of the 80 brace plate disposed upon the rail between the ties, and Fig. 9 is a view of the adjustable member which co-operates with the plate shown in Fig. 8.

My improved compound rail includes a 85 central member or section 1, and side sections or members 2-2 for the said central member 1. The central section 1 includes a base 3 from which is centrally extended a web 4, the said web having its upper edge 90 disposed to lie flush with heads 5 formed upon the upper portions of the side members 2. The base 3 of the section 1 comprises a substantially arch-shaped member, so that the underface of the same is formed with a longitudinally extending channel 6 while the said arch also provides round or curved members disposed each to the opposite sides of the web, and which for convenience, will be termed feet and designated by the numerals 7, and the lower edges of the said feet are horizontally straight.

The outer or side members 2, below their heads 5, are provided with vertically disposed portions 8, the same being parallel 105 with the vertical walls upon the inner faces of the said members, which last mentioned vertical walls are adapted to abut with the straight sides of the web of the inner member 1. The vertical portions 8 are joined 110

- with outwardly rounded portions 8', and the inner walls of the said rounded portions are adapted to engage with the outer rounded faces of the feet 7 of the section 1.
- 5 The portions 8' terminate in inwardly extending flanges or bases 9, while the outer longitudinal and lower edges of the side members are formed with curved or inclined continuous ribs or flanges 10. The upper 10 walls of the inturned base portions or flanges 9 are horizontally straight, receiving the horizontally straight edges of the feet 7, but the underfaces of the said members 9 are beveled or inclined inwardly and 15 upwardly toward the ends of the said base portions 9 and toward the upper horizontally straight faces provided thereby. The base members or flanges 9 do not meet but terminate a suitable distance away from 20 each other and, by an arrangement as below described, it will be noted that the outer longitudinal edges of the flanges 10 provide fulcrum points so that a pressure, such as the weight of the wheels of the rolling 25 stock upon the head of the rail, will have a tendency to swing or tilt the said outer members to force their inner surfaces into tight contact with the outer surfaces of the inner section of the rail.
- 30 The sections comprising the rail, as illustrated in Figs. 1 and 7, are so arranged with relation to each other that the meeting ends or joints of any of the said sections do not come opposite the meeting end or joint of another section, so that all of the joints are 35 broken and consequently a substantially continuous rail is provided.
- It is to be understood that no transverse connecting means is employed for joining 40 the sections of the rails, so that the yieldability or resiliency of the rails will not thus be effected. However I employ tie plates 12 upon which the rails rest. One of these tie plates is positioned upon each 45 of the ties 13, and the said plates include a flat substantially rectangular base portion 14 which is centrally provided, adjacent its opposite transverse ends, with lugs or hooks 15, the inner faces of which being arranged 50 to snugly engage with the outer rounded surfaces of the flanges 10 of the outer sections of the rail. Each of the tie plates to the opposite side of its rail engaging lug is formed with a spike opening 16 through 55 which spikes 17 pass and enter the ties 13. The openings 16 are so arranged that the heads of the spikes will also engage with the flanges 10, forcing the lower corners of the said flanges 10 into tight contact with 60 the chair plate 12 to prevent the lateral movement or tilting of the said rail.
- In order to brace the rail at the portions 65 thereof arranged between the ties as well as to force the upper portions of the sections of the rail in contact with each other I pro-

vide, what I term, a rail plate 18, the same being of a width approximately equaling the width of the rail at the base thereof, and this plate is centrally formed with a longitudinally extending rib 19, the same being centrally formed with a slot or cut-away portion 20 that alines with an opening 21 in the said plate 18. The opening 21 is adapted to receive the rounded and threaded end 22 provided upon a substantially square or rectangular shank 23 of an adjusting member 24. The member 24 includes a head 25 which extends laterally from two of the sides of the rectangular portion of the shank 23 and which preferably has its outer surface round as at 26. The rounded and threaded end 22 of the member 24 is passed through the opening 21 in the plate 18 while the lower portion of the rectangular shank 23 contacts with the straight side walls provided by the cut-away portion 20 in the rib 19, so that the head 26 of the member 24 is disposed at a right angle to the rib 19 and, it should be stated that the width of the member 24 as well as the width of the 90 rib 19 is of a less cross sectional diameter than the distance between the adjacent edges of the inturned flanges or base portions 9 of the outer members of the rail. By arranging the head 26 longitudinally of the 95 edges of the members 9 and inserting the same through the space between the said edges and by rotating the plate 18 to permit of its rib 19 being received between the said adjacent edges of the portions 9 the 100 lower faces 27 of the head 25 will be received upon the upper horizontally straight walls of the said portions 9, while the plate 18 will be arranged transversely of the rail. A washer 28 is arranged upon the lower face 105 of the plate 18, surrounding the threaded end 22 of the member 24, while a nut 30 is screwed upon the said threaded portion 22 and is brought into tight contact with the washer 28. By adjusting the nut 30 the 110 members 9 will be forced toward the plate 18, and the side members will be tilted from their fulcrum points, which, for distinction, are designated by the numerals 32, so that the upper portions of the members comprising 115 the rail will be maintained in proper contacting relation with each other.

From the above description, taken in connection with the accompanying drawings, the simplicity of the device, as well as the 120 advantages thereof will, it is thought, be perfectly apparent to those skilled in the art to which such invention appertains without further detailed description.

Having thus described the invention, what 125 I claim is:

1. A compound rail including a central member provided with feet, side members having their inner faces shaped to receive the inner member, said side members includ- 130

ing inturned flanges upon which the feet of the central member rests, and the underfaces of said side members being beveled inwardly from their outer to their inner edges, as and for the purpose set forth.

2. A compound rail including an inner member comprising a web and a base, said base comprising feet which are inclined in opposite directions from the web, side members having their inner faces shaped to receive the outer sides of the central member, said side members also including inturned base portions upon which the lower edges of the feet rest, and the lower faces of the said inturned portions of the side members being beveled to provide the outer and lower edges of the side members with fulcrum points, as and for the purpose set forth.

3. A compound rail including a central member provided with feet, side members having their inner faces shaped to receive the inner members, said side members including inturned flanges upon which the feet of the central member rest, and the underfaces of said side members being beveled inwardly from their outer to their inner edges, and means arranged upon the base of the rail and co-acting with the inturned portions of the side members for forcing the upper portions of the rail sections in contact with each other.

4. A compound rail comprising a central member and side members, said central member including a base which is channeled centrally and longitudinally forming the same with a pair of spaced feet, a web extending centrally from the base and terminating in a head, side members having their inner faces shaped to coincide with the sides of the central member and being provided with inturned flanges to receive the feet of said central member, and the lower faces of the flanges being beveled from their outer edges inwardly toward their inner edges.

5. A compound rail including a central member having an arched base, and a web, side members having their heads flush with the upper edge of the web, said side members having their inner faces formed to receive the arched base and their lower faces inclined from their outer faces toward the said arched base, and means connecting the base portions of the side members.

6. A compound rail comprising a central member including a web and a base providing members arranged angularly of the web, side members including heads arranged flush with the upper edge of the web of the central member and having their inner faces concaved to receive the angular sides of the base and being further provided with inturned portions upon which the lower edges of the flanges of said base rest, and the lower walls of the sides being beveled in-

wardly from their outer edges to their inner edges, and means for connecting the base portions of the outer sections of the rail.

7. A compound rail including an inner section and side sections, each staggered to break the joints of each of said sections, the central section including a vertically disposed web, and a base portion providing angular members diverging in opposite directions from the web, the side members including heads arranged flush with the upper edge of the web of the central member, and having inturned flanged portions to receive the lower edges of the diverging members comprising the base of the central member, and the said inturned portions having their lower faces beveled toward the outer edges of said sides.

8. A compound rail made up of associated sections having their joints broken, the said rail including a central member having an enlarged base which is channeled to provide the same with feet which are disposed to the opposite sides of the web, the side members having their inner faces shaped to receive the web and the base thereof of the central section, said side members including heads which are arranged flush with the upper edge of the central member, the bases of said side members having their underfaces inclined from their outer edges centrally toward their inner edges, flat tie plates arranged below the inclined base portions of the side members, said plates including lugs which engage with the outer and lower edges of the side members, securing means for the plates, and said securing means engaging with the said edges of the side members of the rail.

9. A compound rail including inner and outer sections having their meeting ends staggered, the central section having a lower arched base, a web extending centrally from the base, the side members including heads which are arranged flush with the upper edge of the web of the central member and having their inner faces conforming to the shape of the base of said central member and receiving the said central member, the lower faces of the sides receiving the central member being beveled from their inner edges toward their outer edges, a horizontally straight plate including a central rib arranged between the adjacent edges of the side members and having the outer edges of the said side members resting thereon, a headed member contacting with the upper faces of the said inturned portions of the outer sections and engaging with the plate, and means for adjusting the said headed member.

10. A compound rail including a central member and side members having their meeting ends arranged in staggered rela-

130

tion with respect to each other, said central member including an arched base, a web extending centrally from the base, side members including heads which are arranged flush with the upper edge of the web of the central member, said side members having their inner faces channeled to agree with the arched base and receive the said base therein, and the bases of said side members being spaced, the lower face of the base being beveled from its outer edge upwardly toward its inner edge, a rail plate arranged transversely on the base of the rail, said plate including a rib disposed between the

inner edges of the bases of the side sections, 15 a headed member having a rectangular shank arranged in a cut-away portion of the rib and having a threaded extension passing through an opening in the said plate, and a nut for the said threaded end all as and for 20 the purpose set forth.

In testimony whereof I affix my signature in presence of two witnesses.

JACOB H. SHANK.
